CLAIM

The ornamental design for a combined portable hand-held personal computer and keyboard cradle mount, as shown and described.

DESCRIPTION

FIG. 1 is a top front and left side perspective view of a combined portable hand-held personal computer and keyboard cradle mount showing our new design with the keys of the portable computer and the pedestal being shown in broken lines for illustrative purposes only and form no part of the claimed design;

FIG. 2 is a top plan view thereof;

FIG. 3 is a front elevational view thereof;

FIG. 4 is a right side elevational view thereof;

FIG. 5 is a rear elevational view thereof; and,

FIG. 6 is a bottom plan view thereof.

FIG. 1

FIG. 2

FIG. 3

FIG. 4

FIG. 5

FIG. 6
